[57] CLAIM

The ornamental design for an accessory work seat for a beautician's chair or the like, as shown and described.

DESCRIPTION

FIG. 1 is a perspective view of an accessory work seat for a beautician's chair or the like showing my new design.

FIG. 2 is a side elevation view thereof.

FIG. 3 is a side elevation view thereof taken from the side opposite that shown in FIG. 2.

FIG. 4 is a top plan view thereof.

FIG. 5 is an end elevation view thereof.

The broken line representation of a beautician's chair shown in FIG. 1 is to illustrate environmental structure only, and is not part of the claimed design.
